UNITED STATES PATENT OFFICE.

ANDREW HOLM, OF CHICAGO, ILLINOIS.

FOLDING METAL BED.

SPECIFICATION forming part of Letters Patent No. 634,110, dated October 3, 1899.

Application filed April 21, 1899. Serial No. 713,828. (No model.)

To all whom it may concern:

Be it known that I, ANDREW HOLM, a citizen of the United States, residing at Chicago, in the county of Cook and State of Illinois, have 5 invented certain new and useful Improvements in Folding Metal Beds; and I do declare the following to be a full, clear, and exact description of the invention, such as will enable others skilled in the art to which it applies to make and use the same.

My present invention relates to improvements in folding beds, and more particularly to that class of which the Letters Patent No. 624,498, granted to me on the 9th day of May, 15 1899, may be taken as a type; and the object is to improve and simplify the construction therein set forth, and thereby increase the utility of the same.

To this end the invention consists in certain 20 features of construction and combination of parts, which will be hereinafter more particularly described and claimed.

In the accompanying drawings the same 25 reference characters indicate the same parts of the invention.

Figure 1 is a side elevation of my improved 30 folding metal bed as it appears set up for use. Fig. 2 shows the bed folded. Fig. 3 is a transverse section on the line 3 3 of Fig. 1. Fig. 35 4 is a detail view of one of the telescoping foot-posts. Fig. 5 is an enlarged detail view of one of the hinged post-joints. Fig. 6 is a similar view of the interchangeable side rail.

The head-piece consists of the rigid corner 35 posts 1 1' and a corresponding intermediate swivel-post 2. The horizontal parallel braces 3, 3', and 3² extend from the solid sockets 1² on the post 1 to the upper half-sections 4 of the hinged sockets a, fixed to the post 2, and 40 the shorter braces 5, 5', and 5² extend from the solid sockets 1³ on the post 1' to the lower half-sections 4', loosely encompassing the post 2 and forming the opposite half of the socket a. This construction practically divides the 45 head into two panels, of which the swivel-post 2 is the dividing-line, and it permits of one panel being folded back upon the other panel to reduce the size for storage, transportation, and the like.

The foot is formed in a somewhat similar 50 manner, except that the posts are formed in two sections consisting of the rigid posts A

and the telescoping sleeves B B², and the intermediate post A of the foot-piece is formed with a notch A' to receive the bent end of the 55 spring-pawl B', fixed on the telescoping sleeve B to limit the upward movement of the telescoping section when it has been raised to the same height as the head-piece, so that both head and foot piece will present a uniform 60 appearance when the bed is folded.

6 denotes the bed-bottom frame, which is provided with the longitudinally-aligned trunnions 7 7, journaled in the sockets 8 8 to permit the bottom being turned up vertically and 65 the head and foot pieces folded in parallel therewith, as shown in Fig. 2.

9 9 denote the sockets, which are formed with the lateral arms 10 10 to support the front edge of the bottom when horizontal. 70

12 denotes the single back or side rail, the opposite ends of which are provided with the lateral tongues 13 13, which are removably secured in the sockets 14 by the set-screws 15. These sockets 14 14 are rigidly fixed to the 75 head-post 1' and to the corresponding foot-post and in the same horizontal plane with the sockets 10 10, which are secured to posts on the opposite end posts of the head and foot pieces. This construction permits of the rail 80 being removed and the head and foot pieces being reversed when desired to fit any particular place.

16 denotes the stationary top of the bed when folded, and 17 the hinged cover, which 85 is folded when the bed is in use and is opened out to cover the upper edge of the mattress and present an ornamental appearance when the bed is folded.

18 denotes a curtain-pole concealed under 90 the projecting flange of the top 16 to receive a sliding curtain and conceal the bed-bottom and springs.

The accompanying drawings show my invention in the best form now known to me; 95 but many changes in the details might be made within the skill of a good mechanic without departing from the spirit of my invention as set forth in the claim at the end of this specification. 100

Having thus fully described my invention, what I claim, and desire to secure by Letters Patent, is—

In a folding bed of the class described, the

horizontally-folding foot-piece provided with a telescopic section; in combination with the head-piece, and the side rails connecting said foot and head pieces, and means for automatically limiting the upward movement of said telescopic section, substantially as and for the purpose set forth.

In testimony whereof I have hereunto set my hand in presence of two subscribing witnesses.

ANDREW HOLM.
